CLAIM

The ornamental design for a backhoe, as shown and described.

DESCRIPTION

FIG. 1 is a right side elevational view of a backhoe, showing our new design;

FIG. 2 is a left side elevational view thereof;

FIG. 3 is a top plan view thereof;

FIG. 4 is a front elevational view thereof;

FIG. 5 is a rear elevational view thereof;

FIG. 6 is a right side elevational view of a second embodiment of the design in FIG. 1;

FIG. 7 is a left side elevational view of FIG. 6;

FIG. 8 is a top plan view of FIG. 6;

FIG. 9 is a front elevational view of FIG. 6;

FIG. 10 is a rear elevational view of FIG. 6.
